UNITED STATES PATENT OFFICE.

STACY B. HASELTINE, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,125,314.

Specification of Letters Patent. Patented Jan. 19, 1915.

Application filed March 10, 1913. Serial No. 753,169.

To all whom it may concern:

Be it known that I, STACY B. HASELTINE, a citizen of the United States, residing at Chicago, in the county of Cook and State of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging, and more particularly to means provided in a draft yoke for forwardly extending a standard freight car draw bar.

In the drawings forming a part of this specification Figure 1 is a side elevation partly in vertical longitudinal section on line 1—1 of Fig. 2 of a draft rigging embodying my invention. Fig. 2 is a plan view partly in horizontal section on line 2—2 of Fig. 1. In Figs. 1 and 2 the parts are in normal position. Fig. 3 is a plan view partly in longitudinal section on line 1—1 of Fig. 2 showing the parts in the position assumed in extreme rearward movement of the draw bar. Fig. 4 is a perspective view of my improved yoke head. Fig. 5 is a perspective view of the filler block.

In the drawings 6, 6 represent draft sills or parts of the car frame to which the draft rigging is applied, 7 the end sill, 8 the buffer block, 9 the draw bar carry iron, 10 the tie plate, 11 the draft gear or compression resisting member, 12 the rear follower, 13 the front follower, 14, 14 stop members provided with the front stop shoulders 15, 15 and rear stop shoulders 16, 16, front limiting stop shoulders 17, 17 and rear limiting stop shoulders 18, 18. 19 represents the draft yoke and 20 the draw bar, having the transverse slot 21 to receive the coupler key 22 by means of which the draft yoke and the draw bar are connected to each other.

The draft yoke 19 comprises a U-shaped draft strap 19^a provided at its rear end with the filler block 23, and having at its forward end a hollow member 24 forwardly provided with a box-like opening 25 to receive the draw bar 20, the said box-like opening having the lateral slots 26, 26 through which the coupler key 22 is passed, the said slots 26, 26 being rearwardly extended to permit the free movement of the coupler key therein in

buffing movement of the draw bar. The said member 24 is provided back of said draw bar opening 25 with a further opening 27 contiguous with the opening 25, which opening 27 is adapted to receive the preferably rectangular filler block 28, which slidably engages therein, and is adapted to contact with the draw bar at its forward end and with the parts within the lateral opening 29 of the draft yoke at its other end. The member 24 is further provided with longitudinal slots 30, 30 opening rearwardly, and adapted to receive the forward or free ends of the yoke strap 22, which are secured therein, by suitable means, preferably the rivets 31, 31.

It will be observed that without change of the stop members or the position of the stop shoulders thereof the standard freight car coupler, when connected to a draft yoke having the means of forwardly extending the coupler key connection therein illustrated and described herein, will be forwardly extended so as to give the proper clearance between cars, which safety requires and at the same time provides a safe and simple means of connecting the draft gear located in its usual position in reference to the stop members with the standard draw bar usually employed in draft rigging for railway freight cars.

On forward movement of the draw bar the draft yoke is drawn forwardly, compressing the parts of the draft gear in the usual manner. On rearward movement of the draw bar the coupler key slides without strain within the slots 26 of the hollow member 24, and the rear end of the draw bar engages with the filler block 28, through which and the front follower 13 the parts within the draft gear are compressed.

I claim:

1. In a draft rigging for railway cars, in combination, a draw-bar, a yoke strap, a yoke head secured to the yoke strap, said yoke head being extended forwardly of the connection with the yoke strap, means slidably connecting the draw-bar with the extensions of said yoke head, and a filler block slidably disposed within the yoke head, free to move both forwardly and rearwardly under buff and draft.

2. In a draft rigging for railway cars, in combination, a draw-bar, a yoke strap, a yoke head, the ends of said strap being attached to the yoke head, said yoke head be-

ing elongated means for attaching the draw-bar to the yoke head, a draft gear within the yoke strap, followers, and a slidable filler block mounted within said yoke head between the front follower and the draw-bar, said filler block being disposed within the yoke head between the points where the

yoke strap is attached to the yoke head and free to move both forwardly and rearwardly with the draw bar.

STACY B. HASELTINE.
